PROGRESSIVE DIE AND METHOD OF
MAKING IT

Arthur D. Johnson, Poway, Calif., assignor to
Solar Aircraft Company, San Diego, Calif., a
corporation of California

Application January 2, 1946, Serial No. 638,618

1 Claim. (Cl. 22-195)

1

This invention relates to the die stamping of sheet metal strips by the process in which the strip to be formed is intermittently fed longitudinally between what are known as progressive forming dies, the dies being brought together to shape longitudinally successive portions of the strip between the intermittent movements thereof, so that when the strip has passed completely through the die it is of uniform cross-sectional contour from end to end.

An object of the invention is to provide progressive dies, the cross-sectional contour of which varies in such manner from end to end thereof that the sheet formed by the dies is gradually worked into the desired shape with relatively little local thinning, thickening, or wrinkling.

Another object is to enable relatively unskilled workmen to make progressive dies of desirably varying cross-sectional contour from end to end.

Other more specific objects and features of the invention will appear from the detailed description to follow of my dies and the method of making them.

Heretofore, progressive dies have been made by skilled craftsmen who shaped the dies or patterns for the dies by hand, so as to obtain a smooth and gradual variation of the cross-sectional contour from end to end of the dies. That method is relatively expensive because highly skilled artisans are required for the shaping operation, and oft times the dies must be repeatedly formed and tested before a shape is arrived at that produces satisfactory results.

In accordance with the present invention, progressive dies having desirable shape can be produced relatively quickly and by a routine procedure capable of being practiced by relatively unskilled workmen. Briefly, the process comprises first forming a pattern of uniform cross-sectional contour throughout, corresponding to the contour of the finished strip to be formed. There is then built up on this pattern a relatively thin and flexible but substantially non-stretchable pattern. The thin flexible pattern, having the configuration of the sheets to be formed, is then distorted by hand so that it gradually varies from the original contour at one end to a simpler contour at the other end. The re-shaped thin flexible pattern is then used as a mold to form a pattern of plaster or the like, which plaster pattern can then be used in accordance with well-known practice to form a metal die. After producing one die or die pattern in the manner described, a complementary die can be prepared from it in accordance with known practices.

2

Referring to the drawing:

Fig. 1 is a perspective view showing a die press containing a pair of complementary, progressive dies for the forming of a sheet metal strip;

Fig. 2 is a plan view of the lower die illustrated in the press of Fig. 1;

Fig. 3 is a cross-section of the die showing the contour of the latter in the planes III-III of Fig. 2 and at all longitudinal points therebetween;

Fig. 4 is a cross-section showing the contour of the die in the plane IV-IV of Fig. 2;

Fig. 5 is a cross-section showing the contour of the die in the plane V-V of Fig. 2;

Fig. 6 is a longitudinal section through a starting pattern showing the initial stage in the preparation of the die of Fig. 2;

Fig. 7 is a view similar to Fig. 6, but showing a second stage in the process;

Fig. 8 is a view similar to Fig. 7, showing a third stage in the process;

Fig. 9 is a view similar to Fig. 8, showing a fourth stage in the process;

Fig. 10 is a view similar to Fig. 9, but showing a fifth stage in the process; and

Fig. 11 is a longitudinal section showing a plaster pattern corresponding to the die of Fig. 2, the section being taken in the plane XI-XI of Fig. 2.

Referring first to Fig. 1, there is shown a conventional sheet metal stamping press 15 containing a lower stationary die 16 and an upper movable die 17. The stationary die 16 is shown resting on a bed 18 of the press, whereas the upper die 17 is secured to the movable platen 19 of the press, so that it can be moved toward and away from the stationary die 16 to form a metal strip 20 as the latter is fed longitudinally between the dies between successive stamping operations.

Referring to Figs. 2 to 5, inclusive, it will be observed that the lower die 16 is curved longitudinally in both the horizontal and the vertical planes, and that its cross-sectional contour varies longitudinally. Thus at the lower or front

end of the die (as viewed in Fig. 2) the working face of the die is flat as indicated in Fig. 5, but in the planes III-III and at all points therebetween, it has a curved contour as shown in Fig. 3. Thus, the die has rather short and deep grooves 21 and 22 near its side edges, these grooves being of irregular shape, and has a high gradual rise 23 in the center. The cross-sectional shape shown in Fig. 3 corresponds exactly to that of the finished strip to be formed between the dies.

The cross-sectional shape of the die varies gradually from the flat shape at the front end as illustrated in Fig. 5, to the plane III—III. Thus, by observing Fig. 4, it will be observed that while the contour is approximately the same as that shown in Fig. 3, the grooves 21 and 22 are much shallower and the rise 23 is not as high.

A pattern identical in shape with the die shown in Fig. 2, can be prepared in accordance with the invention by the following steps:

Referring first to Fig. 6, a plaster pattern 24 having an upper face corresponding in contour to the finished sheet is prepared. In other words, this pattern 24 has a contour throughout its length corresponding to that shown in Fig. 3. The pattern 24 can be prepared by any one of many known procedures which do not constitute a part of the present invention.

As the initial step in the preparation of a progressive die from the pattern 24, a sheet pattern 25 is built up on that longitudinal section of the pattern 24 corresponding to the longitudinal portion extending from the front end to the first plane III—III of Fig. 2, the plane in which Fig. 6 is taken corresponding to the plane XI—XI of Fig. 2. This sheet pattern 25 may consist of wax reinforced with cheesecloth and may be formed by a process set forth in detail in Patent No. 2,383,706, issued August 28, 1945, on "Method of making preliminary shaping die." Briefly, it involves the steps of first brushing a coat of liquid wax on the pattern 24; second, pressing a sheet of cheesecloth into the surface of the wax; third, brushing a second coat of melted wax on top of the cheesecloth; fourth, laying a second sheet of cheesecloth on top of the second layer of wax and pressing it into the wax; and fifth, brushing another coat of melted wax on top of the second sheet of cheesecloth. The second sheet of cheesecloth is preferably laid on the bias with respect to the first sheet so that the warp and weft threads of the cheesecloth in the two sheets are effective as reinforcement to prevent stretching of the sheet in substantially all directions.

Prior to the building up of the sheet pattern 25, a row of nails 26 may be laid points up on the pattern 24 in a line extending across the pattern so that when the pattern has been formed the nails are anchored therein with their points projecting beyond the upper surface of the sheet pattern 25.

Referring to Fig. 7, a layer of plaster 27 is built up on the left end of the pattern 24 and overlapped onto the sheet pattern 25 and the nails 26, so that when the layer 27 of plaster has hardened, it is anchored to the end of the sheet pattern 25 by nails 26. The layer of plaster 27 is preferably substantially thicker than the sheet pattern 25 and has an edge 28 of appreciable width at its line of joinder to the sheet pattern. A row of nails 29 is driven into this edge 28 while the plaster is still soft, as illustrated in Fig. 8.

After the plaster layer 27 has hardened, the unit consisting of it and the sheet pattern 25 is removed from the pattern 24 and flexibly supported for shaping. As shown in Fig. 8, the unit is supported upon bolsters 30 of clay or the like, which bolsters can be re-shaped or changed as necessary to provide the necessary support at the desired points.

The sheet pattern 25 is next shaped by bending it with the hands to gradually flatten it from its left end where it is joined to the plaster layer 27 to its right end. This change in the configu-

ration of the sheet pattern 25 is readily made without stretching the sheet, because the wax is inherently flexible in response to bending forces, particularly when it is warmed, whereas the cheesecloth reinforcement therein offers substantial resistance to stretching.

As the sheet pattern 25 is brought into its final desired shape, additional clay bolsters 30 may be formed thereunder to give it more complete support during the next stage of the operation.

This next stage consists in the building up on top of the sheet pattern 25 of a second layer 31 of plaster, as shown in Fig. 9. This layer 31 is of substantially the same thickness as the layer 27, and the two layers are bound together by the reinforcing nails 29.

After the plaster layer 31 has hardened, the entire unit is inverted as shown in Fig. 10, and supported on bolsters 32 of number and size sufficient to prevent deformation of the unit. Side walls 33 are then built up along the edges of the unit to define therewith a mold box into which plaster may be poured. When the plaster has set, it is removed from the box and inverted as shown in Fig. 11. It constitutes a plaster pattern 34 identical in shape with the die 16 of Fig. 2, and can be used to form a mold in which to cast the die 16 of Fig. 2.

It is to be understood that it is not essential to make the sheet 25 shorter than the starting pattern 24 and fill out with the layer of plaster 27, as has been described. It is often found desirable in practice to form that portion of the pattern that is not to be flattened by means of the plaster layer 27. However, it will be apparent to those skilled in the art that if desired, the sheet pattern 25 can be formed over the whole length of the starting pattern 24 if care is taken in handling not to distort that portion of the sheet pattern 25 that is to be reproduced in its original form.

It will be observed that the entire process beginning with the formation of the sheet pattern in 25 and ending with the finished pattern 34 of Fig. 11, involves only routine operations which do not require any special skill for their proper performance. Furthermore, the process inherently yields a progressive die in which the actual width of the working face of the die is the same in all cross-sectional planes thereof, which means that the sheet metal that is formed in the resultant dies will be shaped substantially by pure bending operations with no compression or stretching of the sheet.

Although for the purpose of explaining the invention, the procedure in accordance therewith has been described in detail, it will be apparent to those skilled in the art that numerous variations from the exact procedure described can be made without departing from the invention which is to be limited only to the extent set forth in the appended claim.

I claim:

The method of making a progressive die, having a working face the transverse contour of which progressively varies longitudinally of the die, from a starting pattern having the same transverse contour throughout as the desired article to be produced by the progressive die, said method comprising the steps of: first, forming on said starting pattern a flexible sheet pattern of substantial length relative to its width into a shape the transverse contour of which is the same throughout and the same as the said article; second, reinforcing a section of said sheet pattern with a

coating of time-setting plaster material on one face thereof to form a section that is non-stretchable and non-compressible; third, removing said sheet pattern from said starting pattern and progressively flattening and widening it between successive longitudinal points thereon beyond the section that has been made noncompressible, to gradually reduce its depth and increase its projected width without materially changing its width along its transverse contour and without changing its length; fourth, reinforcing said sheet pattern with a coating of time-setting plastic material on one face thereof; and fifth, using said progressively flattened sheet pattern as a mold to reproduce its shape in the progressive die to be 15 made.
